US00D658208S

(12) **United States Design Patent**
Moser, III

(10) **Patent No.:** US D658,208 S
(45) **Date of Patent:** ** Apr. 24, 2012

(54) **PORTABLE AIR COMPRESSOR**

(76) Inventor: **John J. Moser, III**, Fort Lauderdale, FL
(US)

(**) Term: **14 Years**

(21) Appl. No.: **29/367,662**

(22) Filed: **Aug. 11, 2010**

(51) LOC (9) Cl. **15-02**

(52) U.S. Cl. **D15/9**

(58) **Field of Classification Search** D15/7-9;
D23/231, 232; 417/410.1, 359, 415-416,
417/234, 321, 265, 405
